UNITED STATES PATENT OFFICE.

CASWELL LEE LEONARD, OF CORINTH, MISSISSIPPI.

POST-ANCHOR.

1,375,398.

Specification of Letters Patent. Patented Apr. 19, 1921.

Application filed February 27, 1920. Serial No. 361,611.

To all whom it may concern:

Be it known that I, CASWELL LEE LEONARD, a citizen of the United States, residing at Corinth, in the county of Alcorn and State of Mississippi, have invented certain new and useful Improvements in Post-Anchors, of which the following is a specification, reference being had therein to the accompanying drawing.

10 This invention relates to anchors and braces for fence posts, and aims to provide a novel and improved means for anchoring a fence post in the ground and for bracing such post against the strains of the fence

15 wires.

Another object is the provision of means for anchoring the end post of a fence in the ground and bracing it to prevent the post being pulled out of place by the tension of the fence, and such anchoring and bracing means requiring but small space, and being located out of the way so as not to extend to any side of the post beyond the end of the fence, such as required with guy wires

25 and the like.

A further object is to provide members carrying the post so arranged as to engage an inclined anchor board or plate which is set in a hole in the ground, whereby to anchor the post to the ground and also brace it against the tensile strain of the fence, without requiring the weight or pressure of stones, dirt or other ballast over the anchoring means to accomplish such results.

30 A still further object is the provision of such means which will support the post above the ground so as not to be subject to rot or decay.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:—

Figure 1 is a side elevation of the improved anchoring and bracing means supporting the post.

Fig. 2 is a horizontal section on the line 2—2 of Fig. 1, showing the anchoring and bracing means in plan view.

55 In carrying out the invention, there is provided a pair of inclined braces 4 which,

as shown, are formed from a bar that is doubled with its terminals uppermost. The upper terminals of these inclined braces 4 overlap the fence post 6 between the upper 60 and lower ends thereof and are secured to opposite sides of the said post by means of a rivet 5, bolt or other securing element. The lower ends of the braces 4 are united by a loop-shaped foot 7 having a broad or 65 widened base. The braces 4 and their foot or loop 7 are located at that side of the post from which the fence extends, so as not to require any space at the other sides of the post.

70 A pair of stays 8 inclined reversely to the braces 4, extend across opposite sides of the post 6 adjacent to the lower end thereof and are secured thereto by means of a rivet 9, bolt or other securing element, similar to 75 the securing element 5, and the upper terminals of the stays 8 overlap the braces 4 near their lower ends or immediately above the foot or loop 7 and are secured thereto by means of a rivet 10, bolt or other securing 80 element. The stays 8 thus rigidly hold the lower end of the post in place, as well as holding the braces 4 in position. The stays 8, like the braces 4, are also bent from a bar or similar length of stock, which is 85 doubled upon itself with the terminals uppermost, and the stays 8 are united at their lower ends by a loop-shaped anchor 11 having a broad or widened base similar to the foot or loop 7. The loop or anchor 11 extends downwardly at an obtuse angle from the stays 8, so as to be nearer the vertical axis of the post 6.

90 In anchoring the post, an inclined anchor board or plate 12 is used, one end portion 95 thereof extending through the anchor 11 with the base of said anchor extending across the lower surface of the board, and the loop or foot 7 rests on the upper surface of said board near the opposite end thereof. 100 The hole 13 is dug in the ground with an inclined bottom, the deeper end being near the post and the shallower end extending in the direction of the fence. This hole need not be very deep, but can be rather shallow 105 if the ground is hard. The base of the anchor 11 is set in the hole adjacent to the deeper-end thereof, and the anchor board or plate 12 is then inserted through said anchor over the base thereof, and laid on the bottom 110 of the hole in an inclined position. The foot 7 can then bear on said board or plate near

the upper end thereof, which will anchor and brace the post. The braces 4 will prevent the movement of the post in the direction of the fence, due to the tensile strain of the fence, because the foot 7 in bearing on the board 12, will brace the post against such movement, and the post can not rise from the ground, because the anchor 11 engages under the anchor board or plate 12, and the lower end of the board or plate can not swing upwardly, because it abuts the end of the hole, being lower down than the opposite end of the board. In other words, with the board or plate 12 in an inclined position, and the ends thereof abutting the ends of the hole 13, the lower end of the board can not be raised, because it must move in an arc that intersects the end of the hole, thus preventing the lower end of the board from being raised. If the ground is soft, abutments 14 of wood, stone or other material can be placed at the ends of the hole for the ends of the board to bear against, to prevent the dirt at the deeper end of the hole giving way. The post is thus anchored even without dirt, stones or other ballast being used over the anchor 11 or board 12, which is contrary to the prevailing practice. In this way, the two bars and board or plate 12 securely retain the posts in place, the anchor 11 in engaging under the lower end portion of the board 12 preventing the post from being raised and the braces 4 and stays 8 preventing the post from being displaced. The tendency for the post to move under the strain of the fence, creates a downward pressure of the foot 7 on the upper end portion of the board 12, and an upward lifting tendency on the anchor 11, both of which strains are resisted due to the board 12 bearing on the ground at the bottom of the hole 13 and abutting the ends of said hole.

Having thus described the invention, what is claimed as new is:—

45 1. In a post anchoring device, the combination with a post, of bars secured to the post, one bar having a loop shaped anchor

below the post and the other bar having a loop-shaped foot at one side of the post, and an anchor plate to be embedded in the ground on which said foot bears, and under which said anchor extends.

2. A post anchoring device comprising a pair of inclined post braces having their lower ends united by a loop-shaped foot to bear on an anchor plate in the ground, reversely inclined stays having their upper ends secured to said braces, and adapted to be secured near their lower ends to the post, and a loop-shaped anchor uniting and extending downwardly from the lower ends of the stays to engage under said plate.

3. In a post anchoring device, the combination with a post, of an inclined anchor plate disposed in a hole in the ground with its ends abutting the ends of the hole, to prevent the lower end from swinging upwardly, an anchor extending from the post and engaging under said plate near the lower end thereof, and bracing means secured to the post and having a foot bearing on said plate near the upper end thereof.

4. In a post anchoring device, the combination with a post, of an inclined anchor plate disposed in a hole in the ground with its ends abutting the ends of said hole to prevent the lower end of said plate swinging upwardly, inclined braces having their upper ends secured to the post and having a loop-shaped foot uniting their lower ends and bearing on said plate near the upper end thereof, reversely-inclined stays having their upper ends secured to said braces and having their lower end portions secured to the post near the lower end thereof, and a loop-shaped anchor extending downwardly from and uniting the lower ends of said stays, and engaging under said plate near the lower end thereof, the lower end of the post being supported above the ground.

In testimony whereof I hereunto affix my signature.

CASWELL LEE LEONARD.
